RAIL ANCHOR

Rolandis A. Blair, Fort Wayne, Ind., assignor to
The P & M Company, Chicago, Ill., a corpora-
tion of Illinois

Application February 11, 1931, Serial No. 514,995
In Great Britain August 20, 1930

14 Claims. (Cl. 238—329)

5 My invention relates to rail anchoring devices adapted to maintain a fixed position on the base portion of a railroad rail and abut against a cross tie to prevent longitudinal creeping movement of the rail, and more particularly to improvements in the rail anchor device shown in Letters Patent No. 1,882,654, granted to me on October 18, 1932.

10 One of the principal objects of the invention is to provide a two-piece rail anchor of the above character in which the rigid member or abutment and the resilient bar member are so formed and engaged with each other that the upward flexing of the jaw end of the resilient bar is restrained to predetermined limits by reason of its 15 engagement with a portion of the rigid member and the under-rail portion of the bar seats on a portion of the rigid member located inwardly with relation to the said restraining portion thereof, whereby the resilience of the said bar and 20 its engagement with the rigid member serve to support the under-rail portion of the bar firmly against the bottom surface of the rail.

25 Another object of the invention is to so form the transverse bar member of the anchor that, when in its applied position on the rail, it exerts pressure on the rigid member transversely of the rail at locations both above and below the edge of the rail base, thereby serving to hold the rigid member from moving outwardly in a direction 30 to loosen its grip on the rail.

35 A further and more specific object of the invention is to provide a device of the above character having an abutment or shoe member and a transverse bar member formed at one end with a hook portion arranged in a wedge relationship with the body of the bar and which is held in assembled relation with the said abutment member by reason of a resilient wedging action of 40 the bar on portions of the abutment member and in which said wedging action is so restrained by the construction of the shoe member as to avoid movement of the under-rail portion of the bar downwardly away from the bottom surface 45 of the rail base.

45 Further objects of the invention will appear from the detailed description of the embodiment shown in the accompanying drawing, wherein:

50 Fig. 1 is a plan view of a base portion of a railroad rail showing a rail anchor device constructed in accordance with my invention applied thereto in a position to bear against an adjacent cross tie.

55 Fig. 2 is a cross sectional view through the base flange of the rail and the abutment member of the rail anchor, as shown in Fig. 1, but illustrating the resilient bar element of the rail anchor in elevation, for the purpose of clearness, and

60 Fig. 3 is a cross sectional view taken on line

3—3 of Fig. 2, looking in the direction indicated by the arrows.

5 The embodiment of the invention illustrated in the drawing is a two-piece device consisting of an abutment or shoe member 10 adapted to engage one base flange of a rail in a position to bear against a vertical face of a cross-tie and a rail base embracing bar 11 adapted to be driven transversely of the rail base 12 to its applied position, and adapted in its applied position by 10 cooperation with portions of the abutment member 10 to lock the abutment in its rail gripping position. The bar 11 may be and preferably is formed of relatively high grade metal, for example, spring steel, and is bent upon itself at 15 one end upwardly and backwardly to provide an upper arm for forming an open loop, designated generally by the reference character 13. The construction of the loop is such as to provide an upper jaw 14 and a lower jaw 14^a which grip 20 the top and bottom surfaces, respectively, of one base flange of the rail when the anchor is in its applied position. Preferably the arm carrying the jaw 14 is of sufficient length and flexibility that the bar can be applied to rails having base 25 flanges of different thicknesses. The said bar 11 may be driven transversely of the rail a distance sufficient to insure a firm grip of the jaws 14 and 14^a on the top and bottom surfaces of the rail base. The other end of the bar 11 is formed 30 with an upturned end portion 15 which, in the applied position of the bar, snaps over the opposite edge of the rail base into engagement with the vertical surface thereof to lock the bar 11 in 35 its applied position, as shown in full lines in Fig. 2 of the drawing. The bar 11 itself has a substantial grip on the top and bottom surfaces of the rail base, but the creep resisting grip is obtained primarily by reason of the wedging engagement 40 of the member 10 on the upper and lower surfaces of the rail base flange, this wedging engagement being maintained through the cooperation of the bar 11 to prevent the abutment member 10 from loosening its hold on the rail.

45 The abutment member 10 is preferably in the form of a casting having spaced plate members 16, 17, either of which may be positioned to engage a vertical face of the cross-tie, depending upon which side of the rail the abutment is applied. The plates 16 and 17 are united by means 50 of cross-bars 16^a and 17^a, spaced apart in vertical arrangement to provide upper and lower bearings 18 and 19, against which the upper and lower jaws of the bar member bear. In this connection it will be noted that the loop 13 of the bar 55 11 is of a wedge form and is adapted to be driven into resilient wedging engagement between the bearing surfaces 18 and 19, the said surfaces serving to restrain excessive upward flexing of the jaw 14. The bearing surface 19 is preferably 60

extended inwardly beneath the base of the rail by forming the plates 16 and 17 with inwardly projecting ledges 20, 21, the upper surfaces of which coincide with the surface 19. By extending the bearing surface 19, the construction presents an arrangement whereby the inner portion 22 of the bearing surface 19 is disposed a substantial distance inwardly from the bearing surface 18. Consequently the wedging engagement of the loop 10 end of the bar between the bearing surfaces 18 and 19 serves to impart a rocking stress to the loop end of the anchor which, due to the laterally spaced arrangement of the bearings, supports the under rail portion of the bar 11 firmly against the bottom surface of the rail base. The loop end 13 of the bar 11 is formed with a diameter somewhat greater than the vertical distance between the bearings 18 and 19. The construction of the loop 13 is also preferably such that the portion 13a thereof extends downwardly and outwardly below the bottom surface of the under-rail portion of the bar when the said bar is in its applied position. Such inclined portion 13a and the oppositely inclined jaw 14, provide converging surfaces 23, 24 which engage the outer edges of the bearing surfaces 18 and 19, respectively, to prevent movement of the abutment member 10 outwardly toward the end of the loop in a direction to loosen its grip on the rail.

30 The abutment member 10 and the bar 11 are normally assembled at the factory by driving the bar 11 between the surfaces 18 and 19 until there is sufficient wedging engagement between said surfaces and the loop end of the bar to hold the parts engaged. In applying the anchor to a rail, the abutment member 10 is first driven to its rail-engaging position, with notches in the edges of the plates 16 and 17 engaging the top and bottom surfaces of the rail whereby upper and lower jaws 25 and 26 provided by such notches in each of said plates are driven into firm wedging engagement with the top and bottom surfaces of the rail base. The application of the member 10 is preferably effected while the bar 11 assumes a position substantially as indicated in dotted lines in Fig. 2. The bar 11 is then driven transversely of the rail by striking the looped end 13 thereof to force the wedge shaped loop between the bearings 18 and 19 of the member 10, the bearing 18 serving to restrain upward flexing of the jaw 14 and consequently increasing its grip on the top surface of the rail base. As soon as the bar 11 is driven transversely of the rail to its normally applied position, the upturned portion 15 snaps over the opposite edge of the rail base, so as to lock both the bar and the abutment member 10 in a position of maximum grip on the rail.

I claim:

60 1. A rail anchor comprising in combination a bar turned backwardly upon itself at one end to provide a jaw for gripping the top surface of one base flange of the rail, and an abutment member having upper and lower bearings spaced laterally of each other transversely of the rail and between which the jaw end of said bar is adapted to be moved into binding engagement therewith, one of said bearings serving to restrain the outward flexing of the jaw portion of said bar and the other said bearing providing a non-yielding support beneath the rail for the under-rail portion of the bar.

70 2. A rail anchor comprising in combination a bar turned backwardly upon itself to form an open loop of substantially wedge form and pro-

viding a jaw for gripping the top surface of one base flange of the rail; and an abutment member having upper and lower bearings spaced laterally of each other transversely of the rail and between which the loop end of said bar is adapted to be moved into binding engagement therewith, the diameter of the loop being greater than the vertical distance between said bearings and having portions above and below the rail base for engagement with the abutment member of the anchor to hold it in its applied position on the rail. 5

3. A rail anchor comprising in combination a bar member formed at one end with upper and lower jaws for gripping one base flange of a rail 15 and provided at the other end with means for locking engagement with an edge portion of the other base flange of the rail, and an abutment member comprising jaw portions spaced apart longitudinally of the rail and embracing the jaw 20 end of said bar, means on a jaw portion of said abutment member projecting beneath the rail to provide a support for the under-rail portion of said bar, and a cross bar extending between the jaw portions of the abutment member providing 25 a restraining member to limit the upward movement of the upper jaw of said bar.

4. A rail anchor comprising in combination a bar member bent at one end to form upper and lower jaws adapted to be driven into gripping 30 engagement with the top and bottom surfaces of the rail base at one side of the rail and provided at the other end with means for locking engagement with the edge of said rail base at the other side of the rail, an abutment member formed with 35 jaw portions adapted to be driven into gripping engagement with the top and bottom of the rail base at opposite sides of the jaw end of said bar, means on the abutment member for restraining upward flexing of the jaw portion of said bar, 40 and means disposed beneath the rail base for supporting the under-rail portion of the bar against the bottom surface of the rail base.

5. A rail anchor comprising in combination a bar member bent at one end to form upper and 45 lower jaws movable transversely of the rail into gripping engagement with the top and bottom surfaces of the rail base at one side of the rail and provided at the other end with means for locking engagement with the edge of said rail base 50 at the other side of the rail, an abutment member formed with jaw portions adapted to be driven into gripping engagement with the top and bottom of the rail base at opposite sides of the jaw end of said bar, means on the abutment 55 member for restraining upward flexing of the jaw portion of said bar during the said transverse movement thereof, and means providing ledges disposed beneath the rail base for supporting the under rail portion of the bar against the bottom 60 surface of the rail base.

6. In a rail anchor, the combination of a bar turned upwardly and backwardly upon itself, to form a loop of substantially resilient wedge form, and an abutment plate member comprising 65 means for gripping the base flange of a rail and having spaced bearings for mounting the member movably on the bar with one of the bearings engaging the body of the bar below the level of the bottom face of the rail and the other engaging the 70 turned back portion of the bar above the level of said bottom face of the rail, serving by a wedging action to limit movement of the abutment plate member toward one end of the bar, said bar being adapted to engage the base flange of the rail at 75.

its opposite end portion for holding said gripping means in operative rail gripping position, and the bottom bearing of said abutment plate member being relatively long and adapted to support the 5 under-rail portion of the bar against the bottom surface of the rail base.

7. A rail anchor comprising in combination a bar member bent at one end to form an upper and a lower jaw adapted to be driven into gripping engagement with the top and bottom surfaces of the rail base at one side of the rail and provided at its other end with means for locking engagement with the edge of said rail base at the other side of the rail, an abutment member comprising 10 two plates, one disposed at either side of the jaw end of said bar, means on the abutment member extending beneath the rail base for supporting the under rail portion of said bar in engagement with the bottom surface of the rail base, and a cross-bar uniting the upper portions 15 of said plates and serving as a restraining member to limit the upward flexing of said jaw member.

8. A rail anchor comprising in combination a bar member bent at one end to form upper and lower jaws adapted to be driven into gripping engagement with the top and bottom surfaces of the rail base at one side of the rail and provided at its other end with means for locking engagement 20 with the opposite edge of the rail base, an abutment member comprising two plates, one disposed at either side of the jaw end of said bar, and means on each of said plates providing a long bearing surface for the under rail portion of the 25 bar to support said bar in firm contact with the bottom surface of the rail base and cross bars uniting the said plates at locations above and below said upper and lower jaws of said bar, one of said cross bars serving as means for restraining upward flexing of the jaw portion of said bar.

40 9. In a rail anchor, the combination of a bar member turned backwardly upon itself at one end to form a depressed loop and a jaw movable transversely of the rail into engagement with the flange at one side of the rail and having a lug portion at its opposite end adapted by engagement 45 with the edge of the flange of the opposite side of the rail to prevent reverse movement of the jaw portion thereof transversely of the rail out of engagement with the flange, and an abutment member comprising two plates at opposite 50 sides of said jaw member, each plate having located on its inner surface a ledge member adapted to hold the bar member against the bottom of the rail base when in applied position, and cross 55 bars extending between said plates in engagement with said jaws serving to hold said jaws from swinging away from each other, whereby the jaws have a strong driving grip on the flange 60 of the rail.

65 10. In a rail anchor, the combination of an abutment member comprising two plate portions arranged in spaced relation to each other and notched to have gripping engagement with the top and bottom faces of the base flange at one side of a rail, a bar member positioned underneath the rail transversely thereof and having one end portion bent upwardly and backwardly upon the bar to provide a loop positioned between 70 said plates and having holding engagement with said abutment member, said bar member being adapted by engagement with the base flange at the opposite side of the rail to hold said abutment member from movement out of engagement

with the rail, and an elongated bearing on the inner face of one of said plate portions of the abutment member underneath the rail and extending transversely of the rail adapted by engagement with a bottom face portion of said bar 5 member to hold said bar member up in holding engagement with the rail.

11. In a rail anchor, the combination of a rail gripping member notched to embrace one flange of a rail base and formed to provide a downwardly-facing seat portion in upwardly spaced relation to said flange and an upwardly-facing seat portion in downwardly spaced relation to said flange and located closer to the central vertical plane through the rail than said first mentioned seat portion, and a transverse member adapted by engagement with said seat portions and with the flange at the opposite side of the rail to hold said gripping member in operative position on the rail. 20

12. A rail anchor comprising, in combination, a resilient bar extending transversely under the rail and bent at one end upwardly and backwardly to provide an arm portion bearing on one of the rail base flanges and having means at its other end bearing on the other rail base flange, and rigid abutment means having upper and lower bearing members adapted by engagement with said bar to hold the abutment means in fixed position with respect to the rail, the upper member 25 bearing on the top side of said arm portion to prevent it from springing away from said bar, the lower bearing member being located nearer the middle part of the rail transversely thereof than the upper bearing member and bearing 30 against the under side of said bar to support it.

13. In a rail anchor, the combination of a retaining member comprising a resilient bar extending transversely under the rail and bent at one end upwardly and backwardly to provide an arm portion bearing on one of the rail base flanges 40 and having means at its other end bearing on the other rail base flange, and rigid abutment means having a seat portion bearing on the top side of said arm portion to prevent it from springing away from said bar, said abutment means having a portion offset to one side with respect to said seat portion and bearing against said retaining member and tending by its pressure on the retaining member to swing the bar against the 45 base of the rail, said inter-engaging portions of said retaining member and said abutment means serving also to hold the abutment means in fixed position with respect to the rail. 50

14. In a rail anchor, the combination of a retaining member comprising a resilient bar extending transversely under the rail and bent at one end upwardly and backwardly to provide an arm portion bearing on one of the rail base flanges and having means at its other end bearing on the other rail base flange, and rigid abutment means having seat portions bearing respectively on the top side of said arm portion and against the bottom face of said bar and adapted by engagement with said retaining member to hold the abutment means in fixed position with respect to the rail, said abutment means also having a portion offset to one side with respect to said seat portions and bearing against said retaining member and tending by its pressure on the retaining member to swing the bar against 65 the base of the rail. 70

ROLANDIS A. BLAIR.
